UNITED STATES PATENT OFFICE.

CHARLES R. MEEKER, OF PITTSBURGH, PENNSYLVANIA, ASSIGNOR TO OIL WELL SUPPLY COMPANY, OF PITTSBURGH, PENNSYLVANIA, A CORPORATION OF PENNSYLVANIA.

WELL PACKER.

Application filed November 11, 1925. Serial No. 68,322.

This invention relates to oil well packers of the type employing a cage loosely mounted on the body of the packer and slip or a plurality of slips carried by the cage; more particularly, the present invention relates to a new and improved cage and slip construction for such packers.

In the use of packers of the character mentioned, it has been found that the engagement 10 of the slips with the pipe or casing has not been as secure or effective as desirable, this is especially so where the interior of the pipe or casing is not uniform or perfectly round. In the cage and slip construction 15 heretofore employed, no means are provided for an independent operation of a slip, that is to say, all of the slips in the operation of expanding them or forcing them against the casing, operate in unison and in a similar 20 manner, consequently should the pipe or casing in which the packer is set be otherwise than perfectly round, the slip contact will be insecure.

Among the objects of my invention are, to 25 provide a cage and slip construction in which the slips have an independent and variable movement in the operation of setting the packer or expanding the slips, and a construction in which each slip may be individually adjusted to make secure contact with the pipe, even though the interior of the pipe 30 be imperfect or not perfectly round.

In the accompanying drawing, which illustrates an application of my invention,

35 Figure 1, is an elevation view of an oil well packer showing the cage and slip construction with the slips collapsed;

Figure 2, a vertical sectional view of the 40 packer showing the packing and slips expanded; and

Figure 3, a detail elevational view particularly showing a slip and the manner of connecting the slip to the cage.

As illustrated, 1 designates the hollow body 45 of a well packer; 2, the lower connecting member; and 3, the upper connecting member; each of said members being threaded to the body 1.

Surrounding the body, and disposed in contact with the upper collar or member 3, is a 50 packing element 4. Packing 4 is held on the body between member 3 and an annular slid-

ing wedge 5, the latter being adapted to be forced downwardly between the upper ends of a series of slips 6 and the body, for the 55 purpose of expanding the slips and causing them to engage the interior of a pipe or casing in which the packer is to be set.

Slips 6 are each formed with a recessed shank portion 7, the recess 8 thereof being 60 disposed centrally of the shank and extending throughout its length. The shank of each of the slips is further provided with bevelled side edges 9 and a curved bevelled bottom edge 10.

Loosely mounted on the body and designed to carry the slips 6, is a cage 11. Cage 11 has a downwardly projecting part 12 adapted to cooperate with a pin 13 on the body for maintaining the slips and the other parts in the 70 position shown by Figure 1, during the act of letting the packer down into a well.

Cage 11 carries the slips 6; said slips being 75 movably connected with the cage by a series of leaf spring members 14.

As shown, each member 14 is fixedly secured at its lower end by rivets 15 or other suitable means to the slip-cage; the upper end of the respective members 14 is flattened and is provided with a central vertically extending slot 16. Slot 16 has a rivet 17 passed therethrough, said rivet extending into the shank portion 7 thus forming a movable engagement between the slip and its member 14 thereby permitting the slip to move longitudinally relatively to its connecting spring member and the cage should a portion of the pipe, otherwise than round, be encountered by the slip in the act of setting the packer. In other words, with the construction just described, I provide each slip with an independent movable engagement between its shank portion and its spring member 14, and also between the respective shanks and the cage.

The prime object of the movable engagement between the slip and its cage is to provide, in addition to the tilting action, a longitudinal or vertical sliding movement between each slip and its cage. It is evident that a vertical sliding movement between the slips and their cage may be effected by reversing the slot and pin construction or by fixedly attaching the upper end of the spring mem-

ber to the shank of the slip and movably securing the lower end of member 14 to the cage.

As shown, and as preferred, the cage is formed with a plurality of slip receiving openings having bevelled or undercut walls 18 and a curved wall 19, said walls 18 being adapted to engage the side edges 9 of the slips and the wall 19 the bottom edge 10 of the respective slips.

What I claim is:—

1. In a packer, a body, a cage loosely mounted on the body, a slip receiving opening in the cage, a slip mounted in the said opening, a spring member having a slot therein, means passed through the slot and movable therein for movably connecting the slip and spring member, and means for fixedly engaging the said member and cage.
2. In a packer, a body, a cage loosely mounted on the body, having a slip receiving opening, a slip carried by the cage and having edges cooperating with the walls of said opening, means connecting the slip and cage whereby a vertical movement of the slip rela-

tively to the cage may be effected including a spring member having a slot therein and a member entered in the slot.

3. In a packer, a body, a cage loosely mounted on the body, slip receiving openings in the cage having undercut walls, slips mounted in the openings having bevelled edges engaging the walls, and means connecting the slips and cage whereby vertical movement of the slips relatively to the cage may be effected, including a spring member having a slot therein and a member entered in the slot.

4. In a packer, a body, a cage having a series of slip receiving openings therein, a series of slips carried by the cage, said slips mounted in said openings and having edges engaging the walls thereof, and means providing a longitudinal sliding engagement between the slips and the cage, said means including independent governing members for regulating the movement of the slips and connecting the slips to the cage.

In testimony whereof I affix my signature.

CHARLES R. MEEKER.
